UNITED STATES PATENT OFFICE.

ALICE H. FLANDERS, OF CHICAGO, ILLINOIS, ASSIGNOR TO A. H. FLANDERS COMPANY, OF CHICAGO, ILLINOIS, A CORPORATION OF ILLINOIS.

DESIGN FOR A WOMAN'S BLOUSE.

54,545.

Specification for Design.

Patented Mar. 2, 1920.

Application filed July 3, 1919. Serial No. 308,662. Term of patent 3½ years.

To all whom it may concern:

Be it known that I, ALICE H. FLANDERS, a citizen of the United States, residing at Chicago, in the county of Cook and State of Illinois, have invented a new, original, and ornamental Design for a Woman's Blouse, (No. 578,) of which the following is a specification, reference being had to the accompanying drawing, forming part thereof.

Fig. 2 is a plan view of the back of the same.

I claim—

The ornamental design for a woman's blouse, as shown.

ALICE H. FLANDERS.
